DESIGN FOR A TRADE-MARK.

The Schedule referred to in these Letters Patent and making part of the same.

To all persons to whom these presents may come:

Be it known that I, EDGAR A. ROBBINS, of Wrentham, in the county of Norfolk, and State of Massachusetts, have invented or produced a new and ornamental Design for a Trade-Mark; and do hereby declare the same to be represented in the accompanying drawings, and thus described:

The constituents of the design are representations of a sheaf of wheat, a plow, a spade, and a rake.

In their arrangement, the sheaf is placed in advance of the plow, the spade, and the rake, and the said spade

and rake are placed saltier-wise, the whole being as represented in the drawing, in which—

a denotes the sheaf, *b*, the plow, *c*, the spade, and *d*, the rake.

I claim the said pictorial arrangement of parts, as described, as my invention or design for a trade-mark.
